Primary Examiner — Garth Rademaker*Assistant Examiner* — Katie S Stofko(74) *Attorney, Agent, or Firm* — NSIP Law(57) **CLAIM**

We claim the ornamental design for a mobile terminal, as shown and described.

DESCRIPTION

FIG. 1 is a front perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

(Continued)

FIG. 7 is a bottom view thereof;

FIG. 8 is a rear perspective view thereof; and,

FIG. 9 is another perspective view thereof in which the display screen of the mobile terminal is shown in an open position.

The broken lines in the figures show portions of the mobile terminal which form no part of the claimed design.
